UNITED STATES PATENT OFFICE.

GEORGE P. BENJAMIN, OF NEW YORK, N. Y.

SPOON.

SPECIFICATION forming part of Letters Patent No. 225,789, dated March 23, 1880.

Application filed December 23, 1879.

To all whom it may concern:

Be it known that I, GEO. P. BENJAMIN, of New York, in the county of New York and State of New York, have invented certain new and useful Improvements in Spoons; and I do hereby declare that the following is a full and exact description thereof, reference being had to the accompanying drawings, making a part of this specification.

10 My invention relates to certain improvements in the construction and application of spoon-handles. It has for its objects economy and strength as well as simplicity of construction.

15 Sheet-metal spoons are common in which the bowl and handle are formed of a single piece, crimped, corrugated, or flanged, to give strength both to the handle and at the point of juncture between the bowl and handle; 20 and sheet-metal bowls with stiff-wire handles have been made in which one end of the wire is turned around and brought back upon itself to form a broad point to grasp, and the other end is riveted to the bowl.

25 My invention relates especially to improvements upon the latter class; and it consists in forming that portion of the handle between the grasping-point and its connection with the bowl of double wire twisted upon itself, said 30 coil or twist being permanently held by welding the ends and forming rivets thereon, and by which the handle is secured to the bowl, as will be hereinafter set forth in detail.

In order that those skilled may understand 35 how to make my improved spoon, I will proceed to describe the same, referring by letters to the accompanying drawings, in which—

Figure 1 is a bottom view of an ordinary basting-spoon embodying the features of my 40 invention; Fig. 2, a central longitudinal section of the same on an increased scale, the grasping portion of the handle being broken away, and Fig. 3 a similar view of a spoon in which the grasping portion of the spoon is 45 made of wood secured to the twisted shank which serves as a screw to hold the wooden grasp.

Similar letters indicate like parts in the several figures.

50 A represents an ordinary sheet-metal spoon-

bowl, the handle of which is formed of wire bent around a former to produce the "grasp" B; thence twisted upon itself, as seen at C, to form the shank, the extreme ends of the wire being welded together at D, and secured by 55 rivets *aa*, formed, preferably, at the same time that the ends of the wire are welded together and out of the stock thus welded, although independent rivets may be used.

In welding the ends of the wire together they 60 are spread sufficiently to give a broad bearing-surface against the bowl, and at the same time formed as near as possible to the contour of said bowl at the said point of contact. The welding of the ends, as described, also 65 serves to prevent the springing apart of the convolutions, and thereby serves to strengthen the handle.

At Fig. 3 I have shown substantially the same construction of handle, with exception of 70 a wooden grasp, E, substituted for the portion B of Fig. 1. This wooden portion is secured by simply turning it up onto the twisted portion C, the convolutions serving as threads to lead and hold said wooden grasp E. 75

I have discovered that handles of equal or greater strength may be made of much smaller wire than is required for the single handle now used, and that the welding of the extreme ends absolutely prevents any tendency of the 80 handle to untwist, and very materially strengthens the whole structure.

After the handle is twisted and secured to the bowl the whole structure is then submerged in a tin-bath in the usual manner, thereby 85 strengthening the several parts and producing a handsome finish.

What I claim as new, and desire to secure by Letters Patent, is—

A sheet-metal bowl or other analogous article provided with a handle composed of wire twisted as described, and welded at the ends, and secured in the manner described. 90

Witness my hand this 17th day of December, A. D. 1879.

GEO. P. BENJAMIN.

In presence of—

F. W. SMITH, Jr.,
Wm. C. MCINTIRE.
